Primary Examiner — Catherine S Posthauer*(74) Attorney, Agent, or Firm* — Hodgson Russ LLP(57) **CLAIM**

The ornamental design for a bag carrier, as shown and described.

DESCRIPTION

FIG. 1 is a front perspective view of a bag carrier, showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 a top plan view thereof; and,

FIG. 7 is a bottom plan view thereof.

The broken lines in the figures illustrate portions of the bag carrier that form no part of the claimed design.

The TOTE-IT logo in the drawings is a registered trademark of James MacDonald and forms no part of the claimed design.

1 Claim, 5 Drawing Sheets(56)
